DESIGN FOR A VELOCIPED

**Knute W. Hedstrom, Gardner, Mass., assignor
to Hedstrom-Union Company, Gardner, Mass.,
a corporation of Massachusetts**

Application March 22, 1938, Serial No. 76,010

Term of patent 7 years

To all whom it may concern:

Be it known that I, Knute W. Hedstrom, a citizen of the United States, residing in Gardner, in the county of Worcester and State of Massachusetts, have invented a new, original, and ornamental Design for a Velocipede, of which the following is a specification, reference being had to the accompanying drawing, forming part thereof.

Fig. 1 is a perspective view of the velocipede showing my new design.

Fig. 2 is a side elevation of the velocipede frame member of Fig. 1.

Fig. 3 is a plan view of the velocipede frame member of Fig. 1.

The dominant feature of my design resides in the frame member shown in full lines.

I claim:

The ornamental design for a velocipede, as shown and described.

KNUTE W. HEDSTROM.
